UNITED STATES PATENT OFFICE.

GEORGE K. HOFF, JR., OF PHILADELPHIA, PENNSYLVANIA, ASSIGNOR TO IDEAL CUP CORPORATION, OF BROOKLYN, NEW YORK, A CORPORATION OF NEW YORK.

METHOD AND APPARATUS FOR PRODUCING FIBER VESSELS.

Application filed December 7, 1923. Serial No. 679,179.

My invention relates to an improved method and apparatus for the production of fiber vessels, for example, paper drinking cups and the like.

5 Heretofore in the production of paper or fiber vessels of the nature of paper drinking cups a relatively large number of operations has been required to form the blank into the finished cup, which not only requires considerable time for the production of a cup, but results in a comparatively high percentage of breakage in production.

In present practice, after the formation of the blank from which the cup, or other vessel, is formed, the blank in a dry condition is passed through a number of operations resulting in a gradual folding of the blank to approximately the form of the vessel to be produced. The incomplete vessel is then coated with paraffine and finally formed in a mould.

Further, the forming apparatus used in present practice is complicated in construction, relatively expensive and more or less difficult to maintain in efficient operating condition.

Now the object of my invention is to provide a method and apparatus whereby the blank, preferably, though not essentially, wet, 30 will be preliminarily preformed in a single operation and the vessel completed immediately thereafter in a mould, to which it will be automatically transferred from the pre-forming device.

35 By virtue of my invention, the rapidity of production may be greatly increased and the percentage of breakage in production substantially eliminated.

Further, by virtue of my invention, the pre-forming and finishing mechanism is comparatively simple in construction, comparatively inexpensive to produce and highly efficient and reliable in operation.

Having now indicated in a general way 45 the nature, purpose and advantages of my invention, I will proceed to a detailed description of a preferred embodiment thereof, with reference to the accompanying drawings, in which—

50 Figure 1 is a general elevation, partly in

section, of cup forming mechanism, embodying my invention.

Figure 2 is a perspective view of a pre-forming die and cooperating fingers.

Figure 3 is a vertical section through the 55 pre-forming die and the final forming or finishing mould, showing the relative positions of these devices and of their several parts.

Figure 4 is a plan view of the pre-forming die indicating the forming of the blank. 60

Figure 5 is a partial plan view of a modified form of pre-forming die and its cooperating fingers.

Figure 6 is a vertical sectional view of the modified form of pre-forming die and fingers 65 illustrated in Figure 5.

Figures 7 and 8 are plan views of a partially formed drinking cup in several stages of its formation.

Figure 9 is a perspective view of a finished 70 drinking cup.

The mechanism to be described comprises essentially two assemblies, the pre-forming die with its cooperating fingers, whereby the blank is creased and folded into approximate 75 form of the cup to be produced, and the finishing mould, comprising male and female members, whereby the folds of the preformed blank are pressed, and the cup finally formed and completed, by turning a flange on its upper edge or lip. 80

The mechanism is supported on a framework *a* which also supports a suitably driven fly wheel *b* connected by means of a link *c* to a slide block *e* supported in suitable guides 85 *d* and adapted to be reciprocated vertically by the rotation of the fly wheel.

Supported by the frame *a* is a table *f* having a central aperture adjacent the edge of which is a circular flange *g*, which forms 90 a seat for the female finishing die or mould member *h*.

Resting on the female mold member *h* is the pre-forming die *i*, provided with depending flange *j* engaging the die member *h* and 95 with oppositely laterally extending ears *k*, *k*, to which are secured the lower ends of upwardly extending guide rods *l*, *l*, the upper ends of which engage a cross member *a'* of the frame work *a*.

An annular head *m* provided with opposite laterally extending slides *n*, *n* which engage the guide rods *l*, *l*, respectively, serves to support the depending preforming fingers *o*.
5 Adjustable stops *p*, *p* are provided on the rods *l*, *l* to limit the downward movement of the fingers *o*. A cross head *q* is spaced above and supported on the head *m*.

Secured to the guide block *e*, by means of 10 a slot and pin connection is a vertically extending connecting rod *r*, journaled in the cross member *a'*, and passing through the cross head *q*, having secured to its lower end a male die or mould member *s*, adapted to be 15 vertically reciprocated. The upper end of the member *s* is adapted, when raised to contact with the crosshead *q* and lift the annular head *m* and fingers *o*.

Referring now more particularly to Figures 20 2, 3 and 4, the preforming die is provided with a central aperture, which is beveled and cut radially to form a series of intercepting arcuate surfaces *u*, and leave the bevelled surfaces *v*, in their extension into the aperture. Between adjacent surfaces *u* are provided inwardly and downwardly extending radial slots *w*.

The preforming fingers *o*, heretofore described as carried by the annular head *m*, comprise 30 flat metal strips arranged to extend downwardly and inwardly at an angle to the vertical, and having their outer edges, adjacent their lower ends, cut away on an arc *x*.

The preforming fingers are, in the forming 35 of a blank, adapted to move with the reciprocating annular head *m* until the laterally extending slides *n*, *n*, abut against the stops *p*, *p*, when they are in a position to cooperate with the preforming die so that 40 when the blank is drawn between the fingers and die by the continued downward movement of the molding member *s* it will be folded to the form shown in Figure 7.

Referring now to Figures 1 and 3, the female finishing die or mould *h* comprises a cylindrical metallic member having in its upper portion a cavity *z* of the form of the finished cup and provided adjacent its upper edge with an annular recess centrally of the 45 bottom of the cavity *z* and extending down through the bottom of the mould member is a bore through which extends a rod *y*, the lower end of which is journaled in a bracket 3 and the upper end of which is provided with a circular head 4, forming an extractor for the female mould. A spiral spring 5 is carried by the rod and held under compression between the bracket 3 and the adjustable stop 6, secured to the rod, which also serves to limit 55 the upward extension of the rod 4, by contact with the lower end of the member *h*.

The male finishing die or mould member *s*, heretofore described, as secured to the end of connecting rod *r*, is in the general form of a 60 frustum of a cone and is provided at its upper

edge with a flange 7 adapted to register with the annular recess of the female member *h*.

The member *s* is bored vertically for the passage of a rod 8 provided with a head 9, forming an extractor. A cavity is provided 70 in the lower end of the member *s* for the reception of a spiral spring 11, which embraces the rod and bears on the upper surface of the head 9. The rod 8 is provided with a vertical slot 12, through which passes a pin 75 13, secured in the member *s*, and which serves to limit the downward extension of the rod.

Referring now to Figures 5 and 6, in which is illustrated a modified form of preforming die and cooperating fingers: The preforming die *i'* is centrally apertured and provided with radial slots *w'*, forming a series of bevelled surfaces *v'*, one of each of the slots being cut away to form an arcuate deflecting surface *u'* extending at an angle to 85 the outer wall of each slot.

The preforming fingers, carried by a head *m'*, comprise downwardly and inwardly extending flat members 14 to the lower ends of which are secured flat curved fingers 15, disposed at an angle to the members 14 and adapted to cooperate with surfaces *u'* and *v'* of the preforming die so that when a blank 90 13 is drawn between the die and fingers, it will be folded to one side, as shown in Figures 5 and 6.

In connection with the form of preforming die and fingers, as shown, in Figures 2, 3 and 4, it is found desirable to give the male die member, which as will be described 100 hereinafter, draws the blank through the preforming die, a slight turn as the blank clears the die. For this purpose, a cam 16 is positioned on the cross member *a'*, at the point where the rod *r* passes through it and a pin 17 is positioned to extend from the rod so that in the descent of the rod, the pin will 105 strike the cam and being deflected thereby will cause the rod and member *s* carried thereby to be turned slightly. A complementary cam 18 causes the rod *r* to be turned back in its upward movement, the slot and pin connection between the rod and block *e* permitting this movement.

In operation, a circular blank from which 115 the cup is to be formed, is cut from the desired paper stock and in a damp or wet condition, with the parts of the machine in the respective positions shown in Figure 1, positioned on the preforming die, as indicated at 120 19, with its central portion supported on the head 4, which is in its upper position. The mechanism is now started and the male mould member moves downwardly, permitting the preforming fingers to move downwardly. 125 As shown in Figure 1, the head 9 proceeds in advance of the mould member and presses the central portion of the blank against the head 4. In the downward movement of the male mould member the preforming fingers 130

descend until stopped by the stops p , p , when they are in cooperative relation with the pre-forming die. In the continued downward movement of the male mould member, the 5 head 9 presses upwardly against its spring by its contact with head 4, until it contacts with the lower end of the member. Further downward movement depresses head 4 within the female mould member against its spring 10 and since the central portion of the blank is caught between the two heads, its outer portion is drawn downwardly between the surfaces of the preforming die and the preforming fingers, as indicated at 10, Figure 3, which 15 drawing operation serves to fold the excess material into a series of folds.

When the blank leaves the preforming die, it has the form shown in Figure 7 with undulations in the side walls thereof. The 20 downward movement of the male mould member continues and the partially formed blank is pushed into the female mould member followed by the male member, which, when fully entered and assisted by the slight 25 turn given thereto by the abutment of pin 17 against the surface of cam 16, the deflection causing the rod r and member s to be turned slightly as hereinbefore described acts to press the folds, and by the entry of the flange 30 7 into the recess t turns a flange on the lip of the cup.

The cup is momentarily pressed and it is preferable that the female mould member be heated in order to dry out the cup and effect 35 a fixing of the folds.

The male mould member is now moved upwardly and the cup is carried with it, the bottom of the cup being held against the head 9 by the head 4. As the male member moves 40 upwardly, its upper end contacts with the cross head q and raises the preforming fingers. In its further upward movement it rises above head 4 and head 9 under the influence of its spring, as member s rises away 45 from it, withdraws the finished cup from the male member. The cup is thus left clamped between heads 9 and 4 until, upon the further upward progress of the member s , pin 13 lifts head 9 and the cup is freed. The finished 50 cup 20 may then be removed by any convenient means.

As indicated, it is sometimes advisable, more especially with a preforming die of the form shown in Figures 2, 3 and 4, to give 55 the male mould member and the partially formed blank held thereto by the head 4, a slight turn as it enters the female mould member. For this purpose the cam 16 and pin 17 are provided, which, in the descent 60 of the male members, contact, causing the male member to be slightly turned, as described, resulting in somewhat compressing the folds so that the partially formed cup assumes the form shown in Figure 8, before

being completely entered in the female 65 mould member and pressed therein.

Having now fully described my invention, what I claim and desire to protect by Letters Patent is—

1. Apparatus for forming fiber vessels comprising in combination, a folding die, a finishing mould comprising male and female members, means to reciprocate the male mould member in relation to the folding die and finishing mould, whereby a blank may be 75 folded and pressed, and means adapted to turn the male member during its entry into the finishing mould.

2. Apparatus for forming fiber vessels comprising in combination, a preforming device 80 adapted to fold a blank, a finishing mould, cooperating members adapted to engage the central portion of a blank, means adapted for drawing the engaged blank through the pre-forming device and cooperating with the 85 finishing mould to press the folds formed in the blank and means adapted to turn said last mentioned means during its preliminary movement of entry into said finishing mould.

3. The method of forming fiber vessels 90 comprising providing a circular blank, supporting the central portion of the blank, drawing the outer portion of the blank over a given path of movement through a folding device whereby it is partially folded and 95 while the central portion of the blank is still supported, continuing the movement of the folded blank in said path of movement and pressing the partially folded outer portion to flatten the folds and simultaneously forming 100 a lip on the vessel.

4. The method of forming fiber vessels comprising providing a circular blank, supporting the central portion of the blank, drawing the outer portion of the blank over a given path of movement through a folding device whereby it is partially folded and 105 while the central portion of the blank is still supported, continuing the movement of the folded blank in said path of movement and 110 pressing the partially folded outer portion to flatten the folds, and simultaneously turning the edge of partially folded blank outwardly to form a flange.

5. In an apparatus for forming fiber vessels, in combination, a mold, a recess therein, said recess having continuous and smooth side walls, a fixed preforming die positioned at the open end of said recess and having a multiplicity of fixed folding elements therein, a reciprocating folding device having a multiplicity of fixed folding elements adapted to co-act with the folding elements of said preforming die to form initial creases 115 in the fibrous material, a smooth surfaced molding member adapted to move longitudinally in said recess, with its smooth surface 120 in close proximity to the inner walls of said 125

recess, and simultaneously turning on its longitudinal axis whereby the initial creases in the paper are flattened and smoothed to their final form.

- 5 6. In an apparatus for forming fiber vessels, in combination, a mold having a smooth walled recess of a configuration corresponding substantially to the shape of the article to be formed, a plug having a smooth outer surface adapted to cooperate with the mold to compress a pleated fiber article between the smooth surfaces of the mold and plug respectively, a die at the open end of said mold centrally apertured to permit the free and unobstructed passage therethrough of the plug, a multiplicity of elements carried by said die, a reciprocating device centrally apertured to permit the free and unobstructed passage therethrough of the plug, a multiplicity of 10 elements carried by said reciprocating device and cooperating with the elements of the die to cause undulations in the fiber sheet at that portion thereof which lies adjacent to the open mouth of the mold, means for supporting a fiber sheet above the die and for drawing it centrally into the mold, means for causing the reciprocating device to approach the die and to impart initial undulations in said sheet during said approach, means to arrest 15 further motion of the reciprocating device, means to cause the plug thereupon to advance into the mold and thereby to draw the fiber sheet through the undulating elements of the die and reciprocating device causing said sheet, in being drawn through said elements, to assume a preliminarily pleated character and then, as the plug completes its advance into the mold, causing the preliminary pleats to be compressed and permanently creased, 20 and means for causing the plug and the reciprocating device to be then withdrawn sufficiently far to permit ready removal of the compressed pleated vessel from the apparatus.
- 25 7. In an apparatus for forming fiber vessels, in combination, a mold having a smooth walled recess of a configuration corresponding substantially to the shape of the article to be formed, a plug having a smooth outer surface adapted to cooperate with the mold to compress a pleated fiber article between the smooth surfaces of the mold and plug respectively, a die at the open end of said mold centrally apertured to permit the free and unobstructed passage therethrough of the plug, a multiplicity of elements carried by said die, a reciprocating device centrally apertured to 30 permit the free and unobstructed passage therethrough of the plug, a multiplicity of elements carried by said reciprocating device and cooperating with the elements of the die to cause undulations in the fiber sheet at that portion thereof which lies adjacent to the open mouth of the mold, means for supporting a fiber sheet above the die and for drawing it centrally into the mold, means for causing the reciprocating device to approach the die and to impart initial undulations in said sheet during said approach, means to arrest 35 further motion of the reciprocating device, means to cause the plug thereupon to advance into the mold and thereby to draw the fiber sheet through the undulating elements of the die and reciprocating device causing said sheet, in being drawn through said elements, to assume a preliminarily pleated character and then, as the plug completes its advance into the mold, causing the preliminary pleats to be compressed and permanently creased, 40 and means for causing the plug and the reciprocating device to be then withdrawn sufficiently far to permit ready removal of the compressed pleated vessel from the apparatus.
- 45 8. Apparatus such as described in claim 6 in which the means for causing approach and recession of the reciprocating device toward and from the die and the means for causing the plug to advance into and withdraw from the mold are cooperatively associated to pass through their respective movements as set forth, upon application to the associated means of reciprocal movement by a single 50 source of power.
- 55 9. In an apparatus for forming fiber vessels, in combination, a mold having a smooth walled recess of a configuration corresponding substantially to the shape of the article to be formed, a plug having a smooth outer surface adapted to cooperate with the mold to compress a pleated fiber article between the smooth surfaces of the mold and plug respectively, a die at the open end of said mold centrally apertured to permit the free and unobstructed passage therethrough of the plug, a multiplicity of elements carried by said die, a reciprocating device centrally apertured to 60 permit the free and unobstructed passage therethrough of the plug, a multiplicity of elements carried by said reciprocating device and cooperating with the elements of the die to cause undulations in the fiber sheet at that portion thereof which lies adjacent to the open mouth of the mold, means for supporting a fiber sheet above the die and for drawing it centrally into the mold, means for causing the reciprocating device to approach the die and to impart initial undulations in said sheet during said approach, means to arrest 65 further motion of the reciprocating device, means to cause the plug thereupon to advance into the mold and thereby to draw the fiber sheet through the undulating elements of the 70

ing it centrally into the mold, means for causing the reciprocating device to approach the die and to impart initial undulations in said sheet during said approach, means to arrest further motion of the reciprocating device, 75 means to cause the plug thereupon to advance into the mold and thereby to draw the fiber sheet through the undulating elements of the die and reciprocating device causing said sheet, in being drawn through said elements, to assume a preliminarily pleated character and then, as the plug completes its advance into the mold, causing the preliminary pleats to be compressed and permanently creased, 80 means operative at an intermediate stage of operation of the last named means for imparting a rotary motion to the plug when the plug has advanced into the mold sufficiently to make contact with the preliminarily pleated vessel therein to cause the preliminary pleats to be laid in the direction of said rotation, and means for causing the plug and the reciprocating device to be then withdrawn sufficiently far to permit ready removal of the compressed pleated vessel from the apparatus. 85

90 8. Apparatus such as described in claim 6 in which the means for causing approach and recession of the reciprocating device toward and from the die and the means for causing the plug to advance into and withdraw from the mold are cooperatively associated to pass through their respective movements as set forth, upon application to the associated means of reciprocal movement by a single 95 source of power.

95 9. In an apparatus for forming fiber vessels, in combination, a mold having a smooth walled recess of a configuration corresponding substantially to the shape of the article to be formed, a plug having a smooth outer surface adapted to cooperate with the mold to compress a pleated fiber article between the smooth surfaces of the mold and plug respectively, a die at the open end of said mold centrally apertured to permit the free and unobstructed passage therethrough of the plug, a multiplicity of elements carried by said die, a reciprocating device centrally apertured to 100 permit the free and unobstructed passage therethrough of the plug, a multiplicity of elements carried by said reciprocating device and cooperating with the elements of the die to cause undulations in the fiber sheet at that portion thereof which lies adjacent to the open mouth of the mold, means for supporting a fiber sheet above the die and for drawing it centrally into the mold, means for causing the reciprocating device to approach the die and to impart initial undulations in said sheet during said approach, means to arrest 105 further motion of the reciprocating device, means to cause the plug thereupon to advance into the mold and thereby to draw the fiber sheet through the undulating elements of the die and reciprocating device causing said sheet, in being drawn through said elements, to assume a preliminarily pleated character and then, as the plug completes its advance into the mold, causing the preliminary pleats to be compressed and permanently creased, 110 and means for causing the plug and the reciprocating device to be then withdrawn sufficiently far to permit ready removal of the compressed pleated vessel from the apparatus.

115 10. In an apparatus for forming fiber vessels, in combination, a mold having a smooth walled recess of a configuration corresponding substantially to the shape of the article to be formed, a plug having a smooth outer surface adapted to cooperate with the mold to compress a pleated fiber article between the smooth surfaces of the mold and plug respectively, a die at the open end of said mold centrally apertured to permit the free and unobstructed passage therethrough of the plug, a multiplicity of elements carried by said die, a reciprocating device centrally apertured to 120 permit the free and unobstructed passage therethrough of the plug, a multiplicity of elements carried by said reciprocating device and cooperating with the elements of the die to cause undulations in the fiber sheet at that portion thereof which lies adjacent to the open mouth of the mold, means for supporting a fiber sheet above the die and for drawing it centrally into the mold, means for causing the reciprocating device to approach the die and to impart initial undulations in said sheet during said approach, means to arrest 125 further motion of the reciprocating device, means to cause the plug thereupon to advance into the mold and thereby to draw the fiber sheet through the undulating elements of the die and reciprocating device causing said sheet, in being drawn through said elements, to assume a preliminarily pleated character and then, as the plug completes its advance into the mold, causing the preliminary pleats to be compressed and permanently creased, 130 and means for causing the plug and the reciprocating device to be then withdrawn sufficiently far to permit ready removal of the compressed pleated vessel from the apparatus.

die and reciprocating device causing said sheet, in being drawn through said elements, to assume a preliminarily pleated character and then, as the plug completes its advance 5 into the mold, causing the preliminary pleats to be compressed and permanently creased, means for causing the plug and the reciprocating device to be then withdrawn sufficiently far to permit ready removal of the compressed pleated vessel from the apparatus, 10 and follower means for causing the pleated vessel to be automatically carried out of the mold as the plug recedes and to be brought to and supported in a free position above the mouth of the mold whence its removal in a lateral direction is unimpeded. 15

In testimony of which invention, I have hereunto set my hand, at Philadelphia, on this 4th day of December, 1923.

GEORGE K. HOFF, JR.
